UNITED STATES PATENT OFFICE.

CHARLES A. SMITH, OF WELLSVILLE, NEW YORK.

RESILIENT TIRE.

1,179,771.

Specification of Letters Patent. Patented Apr. 18, 1916.

Application filed May 15, 1914. Serial No. 838,806.

To all whom it may concern:

Be it known that I, CHARLES A. SMITH, a citizen of the United States, residing at Wellsville, in the county of Allegany and State of New York, have invented certain new and useful Improvements in Resilient Tires, of which the following is a specification.

This invention relates to resilient tires, a principal object of which is to positively preclude puncturing of the tire, nevertheless permitting the tire to be freely flexed under pressure, affording a maximum degree of resiliency.

15 A further object is to provide a sectional elastic tread comprising independent removable sections permitting a section to be removed, as soon as it is rendered unsuitable for use, and replaced by a new one; the sections being transversely grooved to reduce skidding of the vehicle to a minimum.

Still another object is to so construct the cushioning elements and rim member as to permit of the utilization of any desired 25 cushioning means.

Other objects as well as the nature, characteristic features and scope of my invention will be more readily understood from the following description taken in connection with the accompanying drawings and 30 pointed out in the claim forming a part of this specification.

Referring to the drawings: Figure 1 is a fragmentary sectional view of a wheel embodying my invention, Fig. 2 is a transverse sectional view of the same, Fig. 3 is a transverse sectional view of a modified form of cushioning element, illustrating the manner with which it is associated with the inner casing, and Fig. 4 is a detail fragmentary view of the armor ring used in the present invention.

In the drawings wherein is illustrated the preferred embodiment of this invention, 45 a wheel 5 is provided which in the present instance is of the ordinary configuration comprising a hub and spokes, the latter having the outer ends thereof engaged with a felly 6. Associated with the felly 6 is my improved tire, generally designated 7, which comprises a rim, the latter being formed from two complemental sections 8 and 9, respectively, which when engaged, provide a substantially U-shaped structure 50 provided at equidistant points thereon adjacent its outer margins with radially ex-

tending slots 10, the inner periphery of each of said sections 8 and 9 being provided with annular rings 11 and 12, respectively, which when the sections 8 and 9 are 60 engaged provide an annular recess in which the felly 6 is mounted and is secured thereto through the medium of nuts and bolts 13, in order to permit of the expeditious detachment of the sections, if so desired. 65

Mounted in the rim, is a cushioning element supporting base 14, which in the present instance comprises an annular member of the concavo-convex type which has depending from its inner periphery a tapering rib 15, the latter being engaged in a complemental recess in the rim at the jointure of the sections 8 and 9. By the provision of the tapering rib 15, it is seen that the base 14 is retained in spaced relation to the outer face or vertex of the casing, said base 14 likewise tapering toward its marginal edges, in order to facilitate the sliding of the opposite sides 16 of the casing 17 beneath said base 14. The inner 70 casing is preferably made of a flexible material, such as rubber or the like and provides a floating casing which is actuatable when pressure is exerted on the tread of the wheel, said casing 17 being likewise of a 75 substantially U-shaped configuration in cross section, having the vertex thereof lying in parallelism with the vertex of the rim, so as to provide an inclosed chamber in which is mounted a cushioning element. 80 The cushioning element as shown to advantage in Figs. 1 and 2 comprises the ordinary pneumatic tube 18, the latter being engaged with the inner face of the casing 17 and the outer periphery of the base 14, as advantageously illustrated in Fig. 2. 85

An armor ring 19, preferably made of metal is mounted on the outer periphery of the casing 17, said ring being split as indicated at 20 and shown in Fig. 4 to permit the expansion and contraction of the same when pressure is exerted on the tire, said split being diagonal, so as to provide overlapping ends permitting the ring to be readily contracted and allowed to assume 100 its normal position as soon as pressure is released from the tire, the marginal edges of the ring being in engagement with the opposite inner faces of the sections 8 and 9. 105

A tread 21 is mounted on the armor ring 110 19, said tread being preferably made of rubber and comprising a plurality of inde-

pendent sections which are snugly engaged with each other, said sections being held in the outer casing by bolts 22 which extend transversely of the tire through the sections 5 of the tread, one end of said bolt provided with a screw threaded recess in which is adjustably mounted a screw 23 permitting of the removal of any one of the sections when so desired, since as previously pointed 10 out, the bolts 13 may be removed from the felly 6 and the sections 8 and 9, allowing the latter to be disengaged for removing the sections. The tread 21 is mounted for radial movement in the outer casing, since the bolts 22 are engaged through the elongated radially extending slots 10 thereby permitting movement of the tread so as to flex the cushioning element which is mounted in the casing 17, and at the same time, 15 providing an emergency tire which may be used to advantage, since should the pneumatic tube 18 be rendered unsuitable for use, the bolts 22 would provide supports for the tread 21, so as to limit the movement of the latter, at the same time, absorbing the shock to a certain extent in view 20 of the resilient nature of the tread. Each of the sections which comprise the tread 21 is provided at intervals thereon with 25 transverse slots 24, so as to prevent the skidding of the tire, said slots or recesses being preferably of a V-shaped configuration and if desired may be alternately arranged. 30

35 In Fig. 3 is shown a modified form of cushioning element which in conjunction with the casing 17 and the base 14, uses coil springs 25 which are arranged in spaced-apart relation in the chamber which is provided by the inner and outer casings, the inner convolution of each of said springs being engaged with the outer periphery of the base 14 and the outer convolution of each being in engagement with the inner 40 face of a plate 26 which extends around the inner periphery of the casing 17 and is held in engagement therewith by the springs 25. 45

Copies of this patent may be obtained for five cents each, by addressing the "Commissioner of Patents
Washington, D. C."

In use of the form shown in Figs. 1 and 2, when pressure is exerted on the tread 21, 50 the bolts 22 will be actuated causing the flexing of the armor ring 19 and subsequently to the pneumatic tube 18 through the casing 17, the sides 16 of said casing sliding beneath the base 14, in view of the 55 opening which is provided therebetween and the rim by the rib 15. As soon as pressure is released from the outer tread, the casing 17 will assume its normal position as shown to advantage in Fig. 2, in 60 view of the elasticity of the inner tube 18. When pressure is exerted on the tread 21, and the form of cushioning means as shown in Fig. 3 is used, the springs 25 are compressed and automatically expand as soon as 65 pressure is released from the tread. The springs 25 may of course, be engaged by suitable supporting means so as to prevent circumferential or lateral thrust.

It will be understood that the above description and accompanying drawings comprehend only the general and preferred embodiment of my invention and that various minor changes in details of construction, proportion and arrangement of parts may 75 be made within the scope of the appended claim and without sacrificing any of the advantages of my invention.

Having thus fully described my invention what I claim as new and desire to secure 80 by Letters Patent is:

A resilient tire including rim, a floating flexible casing mounted in the rim, a base carried by the rim and lying in spaced relation thereto to permit movement of the 85 inner casing therebeneath, a cushioning element mounted on the base within the casing, and a tread mounted for movement in the rim to flex the cushioning element for absorbing shock from the vehicle. 90

In testimony whereof I affix my signature in presence of two witnesses.

CHARLES A. SMITH.
